CLAIM

The ornamental design for a desktop clock, map, and data base, as shown and described.

DESCRIPTION

FIG. 1 is a front perspective view of the desktop clock, map, and data base showing the new design in a closed storage configuration;

FIG. 2 is a front elevational view of FIG. 1;

FIG. 3 is a left side elevational view of FIG. 1;

FIG. 4 is a right side elevational view of FIG. 1;

FIG. 5 is a rear elevational view of FIG. 1;

FIG. 6 is a top plan view of FIG. 1;

FIG. 7 is a bottom plan view of FIG. 1;

FIG. 8 is a front perspective view of the desktop clock, map, and data base in an open configuration;

FIG. 9 is a left side elevational view of FIG. 8;

FIG. 10 is a right side elevational view of FIG. 8;

FIG. 11 is a top plan view of FIG. 8; and,

FIG. 12 is a bottom plan view of FIG. 8.

The broken line showing of a map and coordinates in FIGS. 1 and 8 is for illustrative purposes only and forms no part of the claimed design.
